UNITED STATES PATENT OFFICE.

GEORGE T. BIGLANE, OF COLLINS, MISSISSIPPI.

THREE-WAY NOZZLE.

Application filed April 14, 1928. Serial No. 276,061.

This invention relates to cotton gins of that type wherein the lint is removed from the gin saws by an air-blast, and more particularly to the nozzles employed in such devices for the purpose of directing the air against the saws.

The invention has for one of its objects to provide a doffing nozzle which will direct the air against the saws in a manner to effect the positive and complete removal of the lint from the saws, and to attain this end, comprehends the provision of a doffing nozzle which will direct three streams of air against each saw, one air stream being directed against the top of the periphery of each saw in a downward and forward direction and the other air streams being directed against the sides of each saw at points above said first point and adjacent 20 the saw teeth.

With the foregoing and other objects in view, the nature of which will appear as the description proceeds, the invention consists in the construction, combination and arrangement of parts hereinafter fully described, claimed and illustrated in the accompanying drawings, wherein:

Figure 1 is a sectional view taken on a plane extending vertically and transversely 30 through a cotton gin equipped with a doffing nozzle constructed in accordance with my invention,

Figure 2 is a view in rear elevation of the doffing nozzle, the air chute,

Figure 3 is a sectional view taken on the vertical plane indicated by the line 3—3 of Figure 2,

Figure 4 is a sectional view taken on the horizontal plane indicated by the line 4—4 of Figure 3,

Figure 5 is a sectional view taken on the vertical plane indicated by the line 5—5 of Figure 2,

Figure 6 is a sectional view taken on the plane indicated by the line 6—6 of Figure 5,

Figure 7 is a sectional view taken on the plane indicated by the line 7—7 of Figure 5,

Figure 8 is a sectional view taken on the plane indicated by the line 8—8 of Figure 5, and

Figures 9 and 10 are detailed sectional perspective views of portions of the doffing nozzle.

Referring in detail to the drawings, 1 55 designates the supporting frame, 2 the roll

box, 3 the ribs, 4 the saws, and 5 the seed-board of a cotton-gin of well-known construction.

The gin is provided with means adapted to permit the removal of the lint from the saws 4 by means of an air-blast, and this means comprises an air chute 6 adapted to receive an air-blast from a suitable blower, and a nozzle 7 adapted to direct the air from the chute against the saws. A take-off chute 8 is located below the air chute 6, and is adapted to receive the lint as it is removed from the saws and convey it to a condenser.

The doffing nozzle 7 inclines downwardly and forwardly from the rear or discharge end of the air chute 6, it has an upwardly and forwardly inclined lower or discharge end arranged at the sides of the saws 4 and across the peripheries thereof, 75

and it gradually decreases in width in the direction of its discharge end to effect an increase in the velocity of the air as it discharges therefrom. The doffing nozzle 7 comprises an arcuate top wall 9, front and rear walls 10 and 11, respectively, and end walls 12. The rear wall 11 is formed to provide exterior parallel channels 13 and interior parallel air passages 14 which extend upwardly from the discharge end of 85 the doffing nozzle 7. The lower ends of the channels 13 receive the peripheries of the saws 4, and the lower ends of the air passages 14 are arranged at opposite sides of the saws. A partition 15 within the doffing nozzle 7 closes the front sides of the lower portions of the air passages 14, and forms in conjunction with the front wall 10 an air passage 16 which is arranged at right angles to the air passages 14 and extends entirely 95 across the doffing nozzle. Triangular blocks 17, which are arranged in the lower end portions of the air passages 14 and contact with the front and rear walls of the passages, provide the passages with discharge ports 100

18 which are arranged at opposite sides of the saws 4. Triangular blocks 19, which are arranged in the lower portion of the air passage 16 between the air passages 14, contact with the front and rear walls of the 105 air passage 16 and provide this passage with discharge ports 20 which are arranged directly above and extend across the peripheries of the saws 4. The blocks 17 and 19 are arranged with their apexes uppermost 110

so as to constrict the air passages 14 and 16 adjacent the discharge ports 18 and 20 and thus permit a further increase in the velocity of the air as it discharges through said ports.

From the foregoing description, taken in connection with the accompanying drawings, it should be apparent that the discharge ports 18 are arranged at opposite sides of 10 and in close proximity to the teeth of the saws 4, and that the discharge ports 20 which are located in advance of and between the discharge ports 18, are arranged directly above and in close proximity to the teeth of 15 the saws. In other words, a series of three discharge ports is provided for each of the saws 4, two of the ports of each series extending transversely of the discharge end of the doffing nozzle and being arranged at 20 opposite sides of the saw teeth and the remaining port of each series extending longitudinally of said end and being arranged directly above the saw teeth. Due to the relative arrangement of the discharge ports 25 and their arrangement with respect to the teeth of the saws 4, the lint is positively and completely removed from the saws by the streams of air discharging from the ports.

While I have described the principle of 30 operation of the invention, together with the device which I now consider to be the best embodiment thereof, I desire to have it understood that the device shown is merely illustrative and that such changes may be 35 made when desired as are within the scope of the invention as claimed.

What I claim as new is:

1. A cotton gin comprising, in combination 40 with the gin saws, an air chute, and a doffing nozzle having discharge ports arranged across the teeth of the saws and discharge ports arranged adjacent the lateral sides of the teeth.

2. A cotton gin comprising, in combination 45 with the gin saws, an air chute, and a doffing nozzle communicating with the air chute and having an inclined discharge end arranged between the sides and across the peripheries of the saws, the doffing nozzle being provided at said end thereof with 50 ports arranged to deliver streams of air against the tops of the saw teeth and ports

arranged to deliver streams of air against the sides of the saw teeth.

3. A cotton gin comprising, in combination 55 with the gin saws, an air chute, and a doffing nozzle having its discharge end arranged in close proximity to the teeth of the saw and provided with channels receiving the saw teeth, the nozzle being provided with 60 discharge ports arranged in front of and at the sides of said channels.

4. A cotton gin comprising, in combination 65 with the gin saws, an air chute, and a doffing nozzle provided with a series of three discharge ports for each saw, certain of the ports extending across the saw and the remainder being arranged at the sides of the saw.

5. A doffing nozzle for a cotton gin provided 70 at its rear side with alternately arranged exterior channels and interior air passages, the channels and air passages extending upwardly from the discharge end of the nozzle, the nozzle being provided forwardly of said first air passages with a second air passage extending entirely across the same, triangular blocks arranged in the lower portions of said first air passages, and triangular blocks arranged in the lower 75 portion of said second air passage at points between said first air passages.

6. A doffing nozzle for a cotton gin provided 80 at its rear side with relatively spaced air passages each having a pair of discharge ports, and provided at its front side with an air passage extending across said first passages and having discharge ports each arranged between each pair of said first discharge ports.

7. A doffing nozzle for a cotton gin provided 85 at its rear side with relatively spaced air passages each having a pair of discharge ports, the nozzle being provided at its front side with an air passage extending across 90 said first air passages and having discharge ports each arranged between each pair of said first discharge ports, and elements arranged in said passages to effect an increase 95 in the velocity of the air as it approaches 100 the discharge ports.

In testimony whereof I affix my signature.

GEORGE T. BIGLANE.
